UNITED STATES PATENT OFFICE.

WILLIAM J. BEMIS, OF SCHENECTADY, NEW YORK.

HOOK FOR CRANE-SLING CHAINS.

Application filed September 15, 1921. Serial No. 500,863.

To all whom it may concern:

Be it known that I, WILLIAM J. BEMIS, of Schenectady, in the county of Schenectady and State of New York, have invented a certain new and useful Improvement in Hooks for Crane-Sling Chains, of which improvement the following is a specification.

My invention relates to hooks for suspending loads on the sling chains of cranes, and its object is to provide a hook of such character as will prevent the slipping off of the hook from a load, or its dislodgement when engaged with a ring, and will reduce liability to injury to operators when hooking on loads.

The improvement claimed is hereinafter fully set forth.

In the accompanying drawing: Figure 1 is a side view, in elevation, of a hook for crane sling chains, illustrating an embodiment of my invention; Fig. 2, a view taken at a right angle to Fig. 1; and, Figs. 3 and 4, transverse sections, on the lines *a a* and *b b*, respectively, of Fig. 1.

In the practice of my invention, referring descriptively to the specific embodiment thereof which is herein exemplified, I provide a hook having a body, 1, which is of the general **U** form of ordinary practice, and has an eye, 1^a, at the extremity of its longer arm, for connection to a crane sling chain. An inwardly extending nose or knob, 1^b, the periphery of which is continuously rounded by being formed in two reversely turned curves, is formed on the upper end of the shorter arm of the hook, the inward projection of said nose or knob correspondingly narrowing the space between the arms of the hook, without presenting any surface or edge in the nature of a barb. A lateral finger grip groove or recess, 1^c, is formed on each side of the body of the hook, extending from its lower portion through about one-half the length of the longer arm, said grooves enabling the hook to be effectively and con-

veniently grasped by the operator at a safe distance from the load to be engaged, when hooking on the load.

The inwardly projecting knob or nose prevents the end of the shorter arm of the hook from becoming engaged with small holes or depressions in the articles to be raised, such as bolt holes in castings, which engagement would cause the load to be carried chiefly by the point or upper end of the shorter arm, and any hole or depression in the article to be lifted, which is sufficiently large to admit the knob, would not engage with it, or prevent the article from dropping to the bottom of the hook, the strength of which would be such as would sustain it. The inwardly extending knob will also prevent the hook from slipping off from loads, or dislodging when hooked up into the ring at the top of the sling, which sometimes happens and causes the hook to fall upon men working below, and by reason of the inward projection at the point, the bending moment, when a load is carried thereon, is reduced, with a corresponding reduction of the tendency to open up the hook due to overloading.

The finger grip grooves on the sides of the hook enable the operator to safely hold it, which he must do when the crane takes up the slack in the chain, and with hooks of the ordinary type, his fingers are endangered in so doing.

I claim as my invention and desire to secure by Letters Patent:

A crane sling hook, having the free end of its bill shaped to form a rounded knob projecting inwardly only, whereby danger of the load becoming hung on the end of the bill and of its slipping off therefrom is obviated.

WM. J. BEMIS.
